UNITED STATES PATENT OFFICE.

JULES MACÉ, OF GRASSE, FRANCE.

LOCK.

1,390,147.

Specification of Letters Patent. Patented Sept. 6, 1921.

Application filed November 4, 1920. Serial No. 421,751.

To all whom it may concern:

Be it known that I, JULES MACÉ, a citizen of the Republic of France, residing at Grasse, Alpes Maritimes, France, have invented a new and useful Lock, of which the following is a specification.

The present invention relates to improvements in locks, and has for an object to provide a key operable lock that will admit of 10 adjustment in a great variety of combinations whereby the same will be baffling to unauthorized persons and those who seek to open a lock by other means than the proper key.

Another object of the invention is to provide a compact and simply constructed lock for carrying out the above objects.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a front elevation of the improved lock;

Fig. 2 is a vertical sectional view therethrough;

Fig. 3 is a horizontal sectional view taken on the line 3—3 in Fig. 2;

Fig. 4 is a fragmentary view showing the adjustment between the tumbler rings;

Fig. 5 is a plan view of one of the end disks of the tumbler;

Fig. 6 is a plan view of the interior ring;

Fig. 7 is a similar view of the outer ring;

Fig. 8 is a plan view of the opposite end ring of the tumbler;

Fig. 9 is a cross sectional view of a modified detail;

Fig. 10 is a fragmentary perspective view of a modified form of latch and associated device;

Fig. 11 is a vertical sectional view through a lock according to a slight modification;

Fig. 12 is a horizontal sectional view through the same lock;

Fig. 13 is a plan view of one of the tumbler disks employed in this modified lock;

Fig. 14 shows a plan view of a partition;

Fig. 15 is an outer ring of one of the modified tumblers; and

Fig. 16 is an inner ring of the same.

Referring more particularly to the draw-

ings; and for the present to Figs. 1 to 8 inclusive, 1 designates a support, such as a door jamb to which the lock casing 2 is secured as by means of screw or other fastening means 3.

In the casing 2 is the usual locking bolt 4 adapted to be projected therebeyond by means of a coöperating rack 5 carried on the shank of the bolt and a pinion 6 carried by a rotatable sleeve 7 which is turned by a handle 8 projecting on the exterior. The sleeve 7 has a slot 8' in which to receive one end of an oscillating latch 9 formed with a central arm 10 which pivots about a pin 11. Pins 12 on the latch 9 receive the free end 70 of a curved flat spring 13 connected to a sleeve 14 also pivoting about the pin 11. The sleeve 14 is connected to an arm 15 which is pivotally connected in turn to a second arm 16 adapted to be reciprocated by 75 an eccentric 17 mounted on the pin 18. As shown in Fig. 1 a handle 19 projecting on the exterior is adapted to turn the eccentric 17.

The upper end of the oscillating latch 9 80 is adapted to fit into slots 20 made in tumblers which are mounted in the upper portion of the casing. The latch 9 normally engages with the peripheral edges of the tumblers inasmuch as the slots 20 are normally out of line and are only brought into registry by the action of a proper key as hereinafter described. The tumblers therefore normally prevent the latch 9 being withdrawn from the slot 8' in the sleeve 7 90 of the bolt actuating mechanism and consequently the bolt is normally held by the latch against movement.

The tumblers are provided with cut out central parts adapted to receive a centering 95 rod 21 which is carried by a plate 22 fitted within a shouldered recess 23 in the rear end of the casing 2, it being held in place by the removable and sliding cover 24. The rod 21 is adapted to slidably receive the tubular key 100 25 which may move axially on and off the rod 21 and is also permitted a rotating movement therearound. The key is provided with a beveled inner end 26 and with a polygonal head 27 at its other end adapted 105 to engage in the polygonal socket 28 of a rotating disk 29 having studs 30 by which to engage the fingers of the operator's hand.

A plate 31 secured as by screws or other fastenings 32 to the support 1 is provided 110

with a flange 33 coöperating with the flange 34 of the disk 29 and also with the outer edge 35 of the disk which overhangs the flange 33. This construction provides for 5 the free rotation of the disk 29 while at the same time holding it effectively in place. The casing 2 is provided with a reduced neck 36 which projects through the support 1 and about the tubular key 25. The neck 10 36 has an internal flange 37 projecting inwardly to engage about the key 25 near the head 27 in order to give proper bearing to the key, but at the same time this internal flange 37 is provided with notches 38 to receive 15 the projections 39 extending outwardly from the key, which projections are shown to be three in number and situated at substantially 120° apart. It will be understood that these notches 38 are for the purpose of 20 permitting of the removal and replacement of the key.

Within the casing 2 are provided a series of tumblers herein shown to be three in number, although they may be added to or subtracted from as conditions dictate or require. 25 Each of these tumblers is composed of a pair of end disks 40 and 41 shown in Figs. 5 and 8 respectively and being generally of the same construction with the exception that whereas the disk 40 is made substantially 30 plain with a central opening 42 and threaded apertures 43 at diametrically opposite points, the other disk 41 is provided with countersunk perforations 44 also at diametrically 35 opposite points, with internal projections 45 extending into the central opening 46, and with bosses or raised parts 47 on its peripheral edge.

The projections 45 are adapted to be 40 countered by the beveled end 26 of the key 25, as hereinafter explained. Fastening devices such as screws 48 have their heads lying in the countersunk openings 44, as shown in Fig. 3, and are threaded into the apertures 43 in the disk 40. The bosses or ridges 47 are preferably irregularly distributed and are rounded off so that they do not interfere 45 with the rotation of the tumblers. The purpose of these bosses or ridges 47 is to confuse 50 and mislead unauthorized persons who obtain access to the lock and who seek to adjust the tumblers without the aid of the key.

Between the end disks 40 and 41 are a 55 number of other disks shown to be three in number, and they are composed of the outer rings 49 shown in Fig. 7 and the inner rings 50 illustrated in Fig. 6. The outer rings 49 are provided with perforations 51 to receive the screws 48 and are made with notches or 60 slots 20 opening through their outer edges and which are adapted to receive, when all 65 of the notches of the various tumblers are brought into registry, the upper end of the latch 9. The inner wall of the outer ring members is made with a number of elongated

slots 52 which open inwardly and are adapted to connect with one or more notches 53 made in the outer edge of the inner ring member 50.

As shown in Fig. 4, a T-shaped key or 70 wedge 54 is adapted to be fitted in one of the slots 52 and the notch 53 which registers opposite the center of such slot 52 in order to bind the inner and outer rings against relative rotation once they have been adjusted. 75 It will be noted from Fig. 4 that the slots 52 and notches 53 are irregularly disposed with reference one to the other in order that minute adjustments may be made of one ring with reference to the other. Filler blocks 80 55 may be placed in the remainder of the slots 52 if desired. On certain of the inner ring members 50 are provided projections 56 extending into the central openings 57 and adapted to coöperate with the projections 39 on the key 25. 85

Partitions 58 embrace opposite ends of the tumblers and are kept spaced apart by division plates 59 which engage the outer edges of the partition plates. All of the plates 90 59 are cut away at 60, as indicated at Fig. 4, in order to allow the latch 9 to engage the tumblers. A spring 61 is fitted between the plate 22 and one of the partitions 58 and serves to yieldingly press the various tumblers against a diaphragm 62 made in the forward portion of the casing 2 and which separates the tumblers from the locking bolt. 95

In the operation of the device the key 25 is inserted through the casing, its beveled 100 end 26 engaging the projections 45 on the end disks 41 of the tumblers thereby causing such tumblers to assume a coaxial position with respect to the key. The projections 39 on the key will be such as to register with 105 the projections 56 on the inner ring members 50 of the tumblers so that as the key is rotated by means of the disk 29 the projections 39 will simultaneously or consecutively come into engagement with the projections 56 and cause the rotation of the tumblers with the key. The points of engagement of the projections will be such with 110 relation to the various tumblers as to bring the slots 20 in the outer ring members 49 115 into alinement, and, after the turning of the disk 29 through several revolutions to be sure all of the slots are in alinement, the disk may be brought to rest, say with the lugs 30 in a horizontal position as shown in 120 Fig. 1 in order that the slots 20 are in the correct position to receive the latch 9.

The handle 19 is then turned in order to 125 actuate the eccentric 17 and cause the lifting of the latch 9 into the slots 20 and the removal of its lower end from the slot 8'. The handle 8 may then be turned and the locking bolt either projected or retracted. Only certain of the tumblers may carry the projections 56, and while I have shown three 130

inner members comprised in each tumbler yet only one ring member in the tumbler is shown as having a projection. The ring members carrying the projections may be 5 interchanged or additional ring members may carry projections and the key 25 is accordingly provided with more or less projections, or it may be altered so that its projections occur at various longitudinal points 10 thereon in order to engage the projections on the inner ring members of the tumblers. In this way the lock may be varied through wide limits, and unless one possesses the particular key it will be difficult to solve the 15 lock.

In opening the lock the handle 19 is generally first partially rotated to turn the eccentric 17, thus moving the connected arms 15 and 16 and partially rotating the sleeve 20 11 by which the spring 13 is moved in a clockwise direction placing the same under tension. Then when the tumblers are rotated by the key into positions to place the slots 20 in alignment, the latch 9 will snap 25 into such registering slots. After the bolt has been locked or unlocked, as the case may be, the tumblers are again moved indiscriminately so as to destroy the alignment of slots 20.

Referring more particularly to Fig. 9, there is herein shown a modification which permits of the opening of the door from the inside without the use of the key. In this instance the latch 9 fits within a pair of sleeves 63 and 64 loosely mounted about the spindle or shaft 65 on which the pinion 6, for rotating the lock and bolt 4, is mounted. The outer sleeve 63 is provided with an opening 66 to allow of the insertion and 40 removal of a set screw 67, the head of which lies in a countersunk recess in the inner sleeve 64.

The sleeves 63 and 64 are also provided with notches 68 to receive the latch 9. The 45 sleeve 64 is normally locked by the set screw 67 to the shaft 65 so that the handle 8 cannot be turned unless and until the latch 9 is removed from the notches 68. However, the set screw 67 may be removed, which will 50 permit the turning of the shaft 65 while the sleeves 63 and 64 remain motionless.

Fig. 10 shows a further modified form of the invention for accomplishing a similar purpose. In this instance the latch is composed of an upper member 69 adapted to engage in the notch 20 in the tumblers while the lower portion of the latch 70 is adapted to engage with the sleeve 7 of the bolt actuating mechanism. The members 69 and 70 55 are not made in one piece as is the latch 9 in the first form of the invention, but these two members 69 and 70 are capable of a relative rotation. The member 69 is fixed to the spindle or shaft 11 while the member 70 is 60 slotted to receive and permit a relative

movement about the shaft 65 and member 69 and is carried by a sleeve 71 fitted loosely on the shaft or spindle 11.

The sleeve 71 is provided with an arm 72 connected by a spring 73 to the similar arm 74 on the spindle. The spring 73 is adapted to hold a hook 75 on the spindle against a pin 76 projecting from a lug 77 on the sleeve 71. A rod 78 is provided to turn the sleeve 71 and consequently the latch member 70 independent of the shaft 11. The rod 78 is on the inside of the door.

When the upper latch member 69 is permitted to enter the notches 20 of the tumblers, the spindle 11 will turn therewith 80 and cause the rotation of the sleeve 71 by the engagement of the pin 76 with the hook 75. This will lift the lower latch 70 out of engagement with the bolt actuating spindle. From inside the door however, the sleeve 71 85 may be independently rotated for this purpose by the rod 78.

Referring more particularly to Figs. 11 to 16 inclusive, a slightly modified form of the lock is shown for securing two plates 79 and 80 together. In this instance the casing is denoted by 81 and is secured as by the screws 82 to the outer face of the plate 80. The front portion of the casing 81 is left open and is adapted to receive a cover plate 90 95 82 provided with an internal cylindrical web 83 passing within the circular wall of the casing 81 and with a flange 84 spaced from the web 83 and providing a circumferential way to receive the outer edge of 100 the casing 81.

A central perforation 85' is made in the cover 82 to receive the centering rod or spindle 85 over which a key, of the form as heretofore described, is adapted to be 105 removably placed. The spindle or rod 85 is carried on a plate 86 located at the back of the casing 81 and fitting a groove 87 provided in the end of the web 83. A shaft 88 projects from the opposite face of the plate 110 86 and passes through the plates 79 and 80, being at its rear end provided with threads 89 to receive a nut 90 secured as by a screw 91 to the rear face of the plate 79. Between the cover 82 and the plate 86 are three tumblers held yieldingly in place by the spring 92 and being separated by partitions 93, shown more particularly in Fig. 14. Division plates 94 are also provided to space the partition plates apart in order to prevent 115 too tight frictional fit of the partitions upon the rotating tumblers. The tumblers are composed of disks 95 shown in Fig. 13, and other disks composed of outer rings 96, shown in Fig. 15, and inner rings 97, shown 120 in Fig. 16. The disks 95 are provided with central openings 98 having centering projections 99 extending thereinto. The disk 95 is also provided with two circular series 125 of perforations 100 and 101 respectively 130

having perforations in a designated number and being arranged in diametrically opposite pairs.

The outer ring 96, shown in Fig. 15, is provided with the bosses 102 and with a series of tapped perforations 103 adjacent an enlarged opening 104 which is provided to receive the inner ring member 97 so that the two ring members extend coaxially and concentrically. The outer ring member 96 is provided with slots 105 to receive the latch as hereinafter referred to.

The inner ring member 97, shown in Fig. 16, has a series of tapped perforations 106, 15 a central opening 107, and a projection 108 extending into this central opening. The perforations 106 in the inner ring member 97 are adapted to aline with the perforations 101 in the disk 95; while the perforations 20 103 in the outer ring member 96 are adapted to be brought into registry with the perforations 100 in said disk 95.

The perforations 103 and 106 are provided preferably in greater numbers than the perforations 100 and 101, but they all aline diametrically so that fastening screws 109 and 110 may pass therethrough for securing the two ring members to the disk 95 as shown in Fig. 11. As also shown in Fig. 11, bolts 25 111 pass through the partitions 93 and division plates 94 respectively for holding these parts together. The latch in this case is made up of a strip of steel or other suitable metal having its central portion looped 30 to provide a bearing 112 extending about a shaft 113 which projects through the cover 82 and is provided with a handle 114 for turning the same.

From the looped intermediate portion 112 40 the two ends of the steel band are brought together and forwardly to provide an arm 115 provided with a tongue 116 engaging the web 83 and with latch portions 117 adapted to enter the slots 105 in the outer ring members 96. The web 83 is provided with a 45 groove 118 extending about the major portion of its circumference and having its end walls adapted to be engaged by a pin 119 on the case so as to limit the turning movement 50 of the cover plate about the case. The cover plate carries the latch with it and to add to the confusion of opening the lock, the latch may be out of a position in which it must necessarily be to register with the slots 105, 55 but an authorized person, knowing the operation of the lock, will turn the cover plate until the pin 119 engages one or the other of the end walls of the groove 118. In this position the latch will be as shown in Fig. 11 so 60 that when the slots 105 in the outer ring members are brought into registry the latch may be moved into the same.

It is obvious that various changes and modifications may be made in the details of 65 construction and design of the above specifici-

cally described embodiment of this invention without departing from the spirit thereof, such changes and modifications being restricted only by the scope of the following claims.

70

What is claimed is:

1. In combination, a movable locking bolt, a latch adapted to hold said bolt against movement, rotatable tumblers supported relatively to said latch whereby to prevent the latter from movement, said tumblers provided with slots therein adapted to be brought into alinement to receive a portion of the latch to permit movement thereof, said tumblers having cutaway central portions, a key fitted through the cutaway central portions of the tumblers, co-operating projections on the key and tumblers adapted to be brought into engagement, said projections on the tumblers being adjustable angularly with respect to the projections on the key, substantially as described.

2. In combination, a movable locking bolt, a latch normally holding the bolt against movement, tumblers placed relatively to the latch to prevent movement thereof, said tumblers composed of a plurality of interchangeable disks, each disk composed of a pair of relatively rotatable inner and outer rings, said outer rings provided with slots in their peripheries, said inner rings provided with projections extending inwardly, means for securing the two rings against relative movement, bosses on the exterior of the outer ring, and a key passing through said tumblers and having outwardly directed projections adapted to co-operate with the projections on the inner rings, substantially as described.

3. In combination, a movable locking bolt, a latch pivotally mounted relatively to the locking bolt and adapted to normally prevent movement of the same, tumblers placed relatively to the latch for normally preventing release thereof, said tumblers provided with slots therein to receive the latch and permit the release thereof, key means co-operating with the tumblers to bring the slots into registry, and eccentric means for swinging the latch into the released position, substantially as described.

4. In combination, a sliding bolt, means to slide the bolt, a latch normally engaged with said last named means and swingingly mounted, an eccentric placed near the latch, a spring connection between the latch and eccentric whereby to yieldingly move the latch into the released position, and key-controlled tumblers placed relatively to the latch and normally preventing its release but provided with slots adapted to be brought into alinement to receive the latch, substantially as described.

5. In combination, a movable bolt, a latch normally preventing the movement of the bolt, tumblers placed relatively to the latch

115
120
125

130

for normally preventing its release but provided with slots adapted to be brought into alinement to receive the latch when moved to the released position, said tumblers provided 5 with central cutaway portions, a centering rod passing through the central portions of the tumblers, a tubular key slidingly fitted over said rod and rotatable thereon, and co-operating projections on the tumblers and 10 key, substantially as described.

6. In combination, a movable bolt, a latch normally preventing the movement of the bolt, tumblers placed relatively to the latch for normally preventing its release but having 15 slots in their peripheries to receive the latch when moved to the released position, said tumblers provided with cutaway central portions, a centering rod passing through the tumblers, a tubular key slidingly 20 fitted over said rod and having a beveled end, said tumblers provided with centering devices adapted to engage the beveled end and the outer surface of said key, and co-operating projections between said tumblers and 25 key, substantially as described.

7. In combination, a casing, a series of partitions therein, tumblers placed between each partition, a plate in the casing, a spring acting against said plate for holding the partitions and tumblers in assembled operative relation, a removable cover for the casing, a centering rod carried by said plate and passing through the tumblers, a tubular key fitted over said centering rod and having a polygonal head, a key rotating device having 30 a polygonal socket for said head, centering devices on the tumblers engaging with said key, co-operating projections on the key and tumblers whereby to rotate the latter, said tumblers having slots in their edges 35 adapted to be brought into alinement, a latch movable into and out of said slots, and a movable bolt adapted to be normally held against movement by said latch, substantially as described.

JULES MACE.
